Fig. 3.

A diagram of a double-pan balance scale. The scale has two weighing pans, one on each side of a central horizontal beam. The left pan contains a weight labeled '20' above it and a weight labeled '27' below it. The right pan contains a weight labeled '20' above it and a weight labeled '8' below it. The beam is supported by two legs at the bottom, each with a small circular base.

UNITED STATES PATENT OFFICE.

LYNFORD HAMILTON, OF PHILADELPHIA, PENNSYLVANIA.

FURNACE ARCH.

Application filed December 31, 1923. Serial No. 683,810.

My invention relates to certain improvements in means for retaining the bricks of a furnace arch in position. The object of the invention is to so design the bricks and the means for supporting the bricks that repairs can be made without drawing the fire of the furnace.

In the accompanying drawings,

Fig. 1 is a longitudinal sectional view of a boiler furnace illustrating my invention;

Fig. 2 is a transverse sectional view on the line 2—2, Fig. 1;

Fig. 3 is an enlarged sectional view of the arch shown in Fig. 1;

Fig. 4 is a sectional view on the line 4—4, Fig. 3;

Fig. 5 is an enlarged sectional view illustrating the means for retaining the bricks at the front of the furnace;

Figs. 6 and 7 are views of the bricks composing the main arch;

Figs. 8 and 9 are views of the tapered bricks of the inner curved section;

Figs. 10, 11 and 12 are views of the bricks of the front section;

Fig. 13 is a perspective view of one of the retaining hooks;

Fig. 14 is a perspective view of one of the bars carrying the main arch; and

Fig. 15 is a perspective view of one of the plates to which the front bricks are attached.

1 is the fire box of a boiler furnace. 2 are the tubes of the boiler. 3 is the grate.

4 is the front of the furnace. 5 is a fuel feeder of any type. 6—6 are transverse overhead beams from which the main arch

7 of the furnace is hung. 8—8 are transverse beams which carry the front section

9. 10 is a fixed section of brick work which is protected and need not be renewed.

Hooked to the lower portions of the beams

6—6 are a series of bars 11, shown in Fig. 14. These bars have permanent hooks 12

45 and removable hooks 13 which engage the beams.

On each bar is a longitudinal rib 14 and at one end of each bar is a curved rib 15.

The ribs have beveled upper surfaces as

50 shown in Figs. 4 and 13. Suspended from the ribs 14 are hooks 16, the heads 17 of the hooks are undercut so as to engage the beveled surface of the ribs. At the lower

55 end of each hook is an arm 18 at right angles to the head 17. The arms are round in cross section, in the present instance, and

extend into holes 19 in the bricks 20, Figs. 6 and 7. The bricks are recessed at 21 to accommodate the hooks 16 and to allow the bricks to have a certain movement on the 60 arms in order that they may be properly located in the arch 7. When the bricks 20 are assembled, as in Fig. 3, one brick retains a hook in an adjoining brick.

When it is desired to remove a brick that 65 has been worn away or cracked, all that is necessary is to detach its hook from the bar 11 and lift it up with the brick, another brick can be placed on the hook and inserted 70 in position without disturbing the furnace fire.

The bricks 22 that form the curved inner portion of the arch are connected by hooks 23 to the curved rib 15, the hooks being 75 made in the same manner as the hooks 16 only shorter.

At the front of the furnace are a series of plates 24 made as shown in Fig. 15. The plates have ribs 25 and a series of projecting lugs 26. The plates are partly embedded in the front wall of the furnace as shown in Fig. 1. At the upper end of each plate are recesses 27 to receive the lower flanges of the beams 8—8. Wedges 28 are driven between the beams and plates retaining the plates in position.

At the lower end of each plate is a rib 29 beveled on its upper surface. Hooks 30 similar to the hooks 16 engage the ribs and have arms which extend into opening 31 in 90 the bricks 32.

The first brick in the series is grooved at 33 in one face so as to engage a ribbed plate 34 secured to the front of the furnace. By the above construction, one brick after 95 another can be set in place from the top.

I claim:

1. The combination in a furnace, of two overhead transverse beams having lower flanges; a series of detachable bars; hooks on said bars engaging the lower flanges of said beams, one hook of each set being detachable, each bar having a longitudinal flange, said flange having a beveled upper surface; a series of bricks forming the body of the arch, said bricks being spaced a considerable distance from the bar so that they can be removed without removing the bars, each brick having a recess and a hole in one side; and long hooks having undercut heads engaging the flanges of the bars and having arms extending into the holes 100 105 110

in the bricks, the body of the hooks being located in the recesses in the bricks.

2. The combination in a furnace, of overhead beams; a series of plates hung from the beams, said plates having flanges at one side, and curved flanges at their lower ends, the side flanges being embedded in the brick work of the furnace; a series of tapered bricks forming a curved portion of

the arch, the first bricks of the series having recesses therein; a ribbed bar on the furnace structure shaped to fit the bricks; hooks engaging the flanges of the plates and the tapered bricks; bricks forming the main body of the arch; and means for supporting the bricks from above.

LYNFORD HAMILTON.
